(57) **CLAIM**

The ornamental design for a display screen with graphical user interface, as shown and described.

DESCRIPTION

FIG. 1 is a front view of a first image in a sequence of a display screen with graphical user interface, showing the claimed design;

FIG. 2 is a front view of a second image thereof;

FIG. 3 is a front view of a third image thereof;

FIG. 4 is a front view of a fourth image thereof;

FIG. 5 is an enlarged front view of a detail indicated in FIG. 3, provided for clarity of illustration;

FIG. 6 is another enlarged front view of a detail indicated in FIG. 3, provided for clarity of illustration;

FIG. 7 is an enlarged front view of a detail indicated in FIG. 4, provided for clarity of illustration; and,

FIG. 8 is another enlarged front view of a detail indicated in FIG. 4, provided for clarity of illustration.

The appearance of the display screen with graphical user interface sequentially transitions between the images shown in FIGS. 1-4. The process or period in which one image transitions to another image forms no part of the claimed design. The dot-dash broken lines illustrate the display screen and form no part of the claimed design. The remaining broken lines illustrate portions of the graphical user interface that form no part of the claimed design.

1 Claim, 8 Drawing Sheets

FIG. 4

Real vs. Fake	
Malachite	
There are a number of different types of crystals some people believe to be filled with their own healing abilities for the mind, body, and soul. Plastic, resin or clay stone can be shaped and dyed like polished malachite. The main differences between real and fake Malachite are illustrated in the table below	
Overview	
Amethyst Real malachite comes in a range of greens from light to dark, but not black. Note the soft layers and uneven patterns.	Purple Scapolite Fake malachite comes in a range of greens from light to dark, but not black. Note the soft layers and uneven patterns.
Iolite Real malachite comes in a range of greens from light to dark, but not black. Note the soft layers and uneven patterns.	Purple Glass Real malachite comes in a range of greens from light to dark, but not black. Note the soft layers and uneven patterns.

FIG. 5

Color	
Amethyst	Purple Soapstone Rough black lines and uniform linear patterns.
iolite	Purple Glass Rough black lines and uniform linear patterns.

Touch test

Real vs. Fake

Malachite

There are a number of different types of crystals some people believe to be filled with their own healing abilities for the mind, body, and soul.

Plastic, resin or clay stone can be shaped and dyed like polished malachite. The main differences between real and fake Malachite are illustrated in the table below

Overview

Real

Real malachite comes in a range of greens from light to dark, but not black. Note the soft layers and uneven patterns.

Fake

Real malachite comes in a range of greens from light to dark, but not black. Note the soft layers and uneven patterns.

FIG. 7

Color	
Real	Fake
Real malachite has a surprising amount of green. Unique patterns of swirls, rings, waves and stripes are distributed throughout the stone face.	Rough black lines and uniform linear patterns.
Touch test	
Real	Fake
Cold to the touch for a few seconds.	Warm to the touch in the case of plastic—made fakes or clay stones. Cold to the touch in the case of glass but for the first second only.
Specific gravity	
Real	Fake
3.6 — 4.05 g/cm ³ , real malachite should feel heavy, dense due to its high copper content.	Since many malachite imitations are made of plastic, glass or clay, they are much lighter than you might expect from real malachite.
Acid test	
Real	Fake
If you place a drop of hydrochloric acid on powdered malachite, a visible fizz will occur.	Imitations created from plastic or glass won't produce a fizz with a drop of hydrochloric acid.

FIG. 8
